UNITED STATES PATENT OFFICE

168,199

SPOON OR SIMILAR ARTICLE OF FLATWARE

Marion Weeber, New York, N. Y., assignor to National Silver Company, New York, N. Y., a corporation of New York

Application March 18, 1952, Serial No. 19,020

Term of patent 14 years

(Cl. D54—12)

To all whom it may concern:

Be it known that I, Marion Weeber, a citizen of the United States, residing in the city, county, and State of New York, have invented a new, original, and ornamental Design for a Spoon or Similar Article of Flatware, of which the following is a specification, reference being had to the accompanying drawing, forming a part hereof, in which:

Fig. 1 is a front elevational view of a spoon, showing the essential features of my new design in full lines.

Fig. 2 is a cross-sectional view taken on line 2—2 of Fig. 1.

The back of the spoon is conventionally plain.

I claim:

The ornamental design for a spoon or similar article of flatware, as shown and described.

MARION WEEBER.
